F. VAN CAUWENBERGH.
CLAMP FOR VISES AND OTHER ARTICLES.
APPLICATION FILED JULY 3, 1916.

1,245,828.

Patented Nov. 6, 1917.

UNITED STATES PATENT OFFICE.

FRANK VAN CAUWENBERGH, OF ROCKFORD, ILLINOIS.

CLAMP FOR VISES AND OTHER ARTICLES.

1,245,828.

Specification of Letters Patent.

Patented Nov. 6, 1917.

Application filed July 3, 1916. Serial No. 107,304.

To all whom it may concern:

Be it known that I, FRANK VAN CAUWENBERGH, a citizen of the United States, residing at Rockford, in the county of Winnebago and State of Illinois, have invented 5 certain new and useful Improvements in Clamps for Vises and other Articles, of which the following is a specification.

In the pursuit of various trades workmen 10 who employ vises and other tools often desire to use the same in places remote from their work benches; and this is especially true in the case of plumbers and repair men whose work brings them to places where 15 bench vises are not accessible.

My invention aims to provide means for mounting on any suitable support a vise or similar tool or work support wherever the workmen may be employed. In other words, 20 I have provided means by which a vise or other article may be easily attached to any of a large variety of fixed supports, such as to a post, pipe, plank, ledge, etc.

My invention also contemplates the provision of a supporting means of this character in the form of a screw clamp equipped with novel means for attachment of a vise thereto, whereby the vise may be supported in upright position regardless of whether the 30 clamp is attached to the support in any of a plurality of different positions necessitated by reason of the shape or position of the said support.

Referring to the drawing,—

35 Figure 1 is a side view of a clamp supporting a vise according to my invention;

Fig. 2 is a plan view of the clamping device; and

Fig. 3 is a sectional view taken on the line 40 3—3 of Fig. 1.

While I have illustrated my improvements as supporting a vise of the character described in my Patent No. 828,787, it should be understood that the invention is not limited 45 to this purpose, since my improved clamp may be used for supporting any of various tools, work supports and the like as will be readily apparent hereinafter.

The clamp, of the well known "C" type, 50 consists of a body 4, one arm 5 of which constitutes the fixed jaw of the clamp. The other arm 6 forming the nut, carries the screw 7 to which is connected through the agency of a ball joint 8, the movable jaw 9 55 which is braced by a sliding connection 11 with the flange 12 of the clamp body. In

the present instance, the clamp is shown secured to a horizontal pipe 13.

The vise shown consists, generally stated, of jaws 14 and 15 connected by threaded rods 16 and 17 that are adapted to be operated by nuts 18 and 19 and the cam lever 21 for tightening the jaws to very forcibly compress the jaws as described in my patent mentioned above. The jaw 14 is formed 65 with an integral head 22 shaped to provide vertically extending and tapered side faces 23, best shown in Fig. 3. The vise through the agency of this head 22 is adapted to be detachably interlocked with the clamp in a 70 manner which will now be described.

The means on the clamp enabling the vise to be interlocked therewith is disposed at the elbow of the clamp adjacent to its fixed jaw so that the point of attachment is disposed in close proximity to the point of attachment of the clamp to its means of support. Also by utilizing this corner of the clamp for the vise attachment two adjoining 75 sides of the vise are available and are best adapted for this purpose. Formed integral with this corner of the clamp is a pair of heads designated generally by reference characters 24 and 25 arranged in right angular relation and each provided with a 80 plurality of sockets into any of which the head 22 of the vise is adapted to be inserted. As shown in Figs. 2 and 3, each head 24 and 25 is provided with four sockets 26 spaced quarteringly, each socket having side 90 faces 27 tapering or converging inwardly and having reduced openings 28. Each socket is shaped to conform to the taper of the head 22 of the vise and to fittingly receive said head. In other words, the head 95 of the vise is adapted to be inserted into any socket in the clamp heads 24 and 25 from the outer end of said sockets, and in the instance shown in the drawing the vise head is inserted in the uppermost socket of 100 the head 25. It will be noted viewing Fig. 3, that the upper portion of the side faces 23 of the head 22 fittingly engage the walls of the uppermost socket, while the lower portion of said sides merely engages beneath 105 the reduced mouth portions thereof. Thus the head 22 is rigidly secured in both the upper and lower sockets against lateral displacement. A pin 29 may be passed through the head 22 immediately beneath the lower 110 edge of the upper socket in which the head is engaged, as shown in Fig. 3, for the pur-

pose of preventing withdrawal of the head from the socket. The vise is thus rigidly secured to the clamp. Since there are four sockets on each head on the clamp, it follows that the vise may be attached to clamp in eight different positions relatively thereto. By reason of this provision for interlocking the vise and clamp, the vise may always be mounted in upright position irrespective of whether the support to which the clamp is attached extends in a vertical or horizontal direction or whether the screw end of the clamp must on account of limited space be positioned either to one or the other side of the support.

I claim:

1. The combination of a vise or other article and a clamp support therefor, the rigid element of the article being formed with a 20 tapered head having a reduced neck so as to provide tapered projecting sides, the clamp being shaped to provide a pair of integral heads having faces relatively arranged at substantially right angles and each provided 25 with a series of radially arranged sockets respectively tapering toward the center of

the head so as to fittingly receive the tapering head of the article, the sockets of each head on opposite sides of the center thereof being in alinement and so shaped that when 30 the tapered head of the article is inserted in one socket the tapered sides of said head will extend beyond said socket and will engage in the inner end of the opposite or alined socket.

2. The combination of a vise or other article and a clamp support therefor, the rigid element of the article being formed with a tapered head having a reduced neck so as to provide tapered projecting sides, the clamp 40 being equipped with a head having sockets quarteringly arranged and tapered inwardly from their outer ends so that the tapered head of the face may be inserted into the outer end of any socket, the sockets being 45 so shaped that said tapered head will, when fittingly engaged in the socket, extend therethrough and engage in the inner end of the opposite socket so as to insure rigidity in the socket connection.

FRANK VAN CAUWENBERGH.
